SWITCH ROD CONNECTION TO SWITCH POINT

George Arnold, Shaker Heights, Harry A. Schultz, Garfield Heights, and Howard I. Prentice, Beechwood Village, Ohio, assignors to Cleveland Frog & Crossing Co., Cleveland, Ohio, a corporation of Ohio

Application October 2, 1944, Serial No. 556,748

7 Claims. (CL. 287—20.5)

1

This invention relates to railway switches and more particularly to improved and novel switch clips or lugs for connecting the switch rods to the switch points thereof.

An object of the invention is to provide in a railway switch improved and novel switch clips or lugs for connecting the switch rods to the switch points and which clips or lugs may be in the form of a one-piece casting or forging if desired and do not include pivot pin and socket connections or other parts which may be subject to excessive wear or damaged or broken readily in use; said clips or lugs being so designed that they can take different angular positions relative to the switch points to which they are secured during the throwing of the switch without the creation of high stresses in the parts but are held at all times in tight engaging contact with said switch points.

Another important object is to provide in a railway switch improved and novel switch clips or lugs for connecting the switch rods to the switch points in such manner that wear of the parts is reduced to a minimum.

Another object is to provide a railway switch wherein the switch points can be thrown easily, positively and with a minimum strain and wear on the parts.

An additional object is to provide improved and novel switch clips or lugs for connecting switch rods to the switch points of railway switches in a way to lengthen the life of the switch installations by eliminating or reducing the incidence of breakage or of damage to the parts through bending, shearing or the like and especially by obviating the use in the clips or lugs of swivel pin and socket connections.

A further and general object is to provide for railway switches, switch clips or lugs of the character hereinbefore referred to and which clips or lugs are of relatively simple design, can be economically manufactured, are reversible for either right or left hand application, can be installed with facility and dispatch and after installation are susceptible of ready adjustment and maintenance.

Further and additional objects of the invention and other advantages to be derived therefrom will become apparent during the detailed descriptions of several illustrative embodiments thereof which are to follow.

Referring to the accompanying drawings illustrating said embodiments,

Fig. 1 is a top plan view of one form of railway switch to which the invention may be applied and

2

shows one construction of switch clips or lugs embodying the invention and utilized for connecting the switch rods to the switch points.

Fig. 2 is a view taken on line 2—2 of Fig. 1 looking in the direction of the arrows and is partly in section and partly in elevation.

Fig. 3 is a fragmentary sectional view similar to the left hand portion of Fig. 2, on a larger scale than either Fig. 1 or Fig. 2.

10 Fig. 4 is a fragmentary top plan view of Fig. 3 with certain portions broken away and shown in section.

15 Fig. 5 is a fragmentary elevational and sectional view with the section taken on lines 5—5 of Figs. 1 and 4 looking in the direction of the arrows.

Fig. 6 is a view similar to Fig. 3 but showing for further illustrative purposes a different embodiment of the invention than is depicted in the previous views.

20 Fig. 7 is a view partly in top plan of Fig. 6 and partly in section.

Fig. 8 is a view partly in section and partly in side elevation and is taken approximately on line 8—8 of Fig. 7 looking in the direction of the arrows.

25 Fig. 9 is a diagrammatic view illustrating the rocking movements of the switch clips or lugs of the invention and the relationship of the parts when the switch is thrown.

30 Fig. 10 is a detached perspective view of the lower portion of the embodiment of the invention illustrated in Figs. 6—8, and

Fig. 11 is a detached inverted perspective view of the upper portion of the embodiment of the invention illustrated in Figs. 6—8.

35 The invention contemplates the use of switch clips or lugs which may be in the form of a one-piece casting or forging and which do not include pivot pin and socket connections or other parts such as heretofore used in switch clip connections and which are subject to wear or which may be readily damaged. The switch clips or lugs embodying the present invention are provided with a curved or other surface which bears against the switch point and enables the clips or lugs to take different angular positions relative to the switch points.

40 The invention further contemplates the use of horizontal bolts spaced longitudinally of the clips or lugs and the switch points and utilizing spring means or some equivalent resilient means to hold such curved or other surface of the clips or lugs firmly in contact with the switch points at all times. The clips or lugs in taking their different angular positions relative to the switch points will

have a rolling or rocking movement on the switch points rather than a sliding movement thereon thus reducing the wear on the parts, facilitating the throwing of the switch and diminishing the creation of stresses in the clips or lugs and the switch rods. As previously stated the clips or lugs do not include swivel pin and socket connections between the switch points and the clips or lugs or between the latter and the switch rods and thus a construction is provided that does not have elements which are subject to excessive wear or are likely to be sheared or damaged during use.

In order to make the invention more apparent to those skilled in the art two of the various forms of construction which may embody the invention will be described in detail.

Referring particularly to Fig. 1, there is shown one type of railway switch equipped with devices embodying the invention but it will be understood that other types of switches also might be so equipped. The type of switch construction described herein as an example includes the stock or main rails 10 and 11 and the movable switch points 12 and 13 which cooperate with said rails respectively depending upon the thrown position of the switch. The rails are supported by the usual ties 14 and preferably will bear upon tie plates. The stock or main rails 10 and 11 are shown as of standard T section, while the switch points 12 and 13 may be of standard T section suitably planed and shaped to cooperate with the main rails. Each point is provided with reenforcing bars 15 and 16 secured thereto by suitable means, with the bars 15 on the sides of the switch points adjacent to the main or stock rails while the bars 16 are located on the inner sides of the points.

The switch points 12 and 13 are connected by switch rods 17 and 18, with the latter rod shown extended beyond the rail 11, as indicated at 18a and operatively connected to an element 19 of the switch throwing mechanism. Although two switch rods have been shown it will be understood that in some installations a different number of rods may be employed. The rods may be formed in one piece or they may be formed of sections joined by an insulating connection as shown herein. The rods may be formed of flat bar steel and disposed either horizontally or vertically, the latter disposition of the rods being indicated herein as it is deemed preferable, although it does not form any part of the present invention.

The switch construction heretofore described is well understood by those skilled in the art and its construction and mode of operation need not be explained in greater detail.

The switch clips or lugs will be described now, it being understood that the lugs which are connected to the switch points 12 and 13 are identical and that therefore only one clip or lug need be described as, for instance, the clip or lug which is attached to switch point 12. It will further be understood that the clips or lugs are interchangeable and are not made as right or left hand parts, a fact which promotes efficient and economic production and facilitates installation.

The switch clips or lugs may be steel or other castings or forgings and those shown in Figs. 1 to 5 inclusive comprise a vertically disposed connecting portion 20 which straddles the switch rod, a switch point contacting portion 21 located at a higher level than the connecting portion and

extending transversely thereof and an intermediate portion 22 arranged in the same vertical plane as the connecting portion and merging with the contacting portion centrally of the ends thereof.

It will be noted that the construction of the switch clip or lug is such that the thrust of the switch rod or tie bar is applied to the switch point relatively high up on the latter. This arrangement is important in view of the wide use of high rails. In switch installations where the rails are relatively high as, for example, six, seven or eight inches in height, there is a tendency for the switch points to roll over unless the thrust of the switch rods or tie bars is applied to the switch points at a relatively high location. The present construction adequately takes care of this tendency of the switch points to roll over since the thrust of the tie bar or switch rod is applied through the switch clip or lug well toward the top of the switch points.

The connecting portion 20, as already stated, straddles the switch rod or tie bar 18 or 17, as the case may be, and since the wide dimension of said rods or bars is vertically disposed in this instance the said connecting portion 20 is also vertically disposed, it being understood that when the clip or lug is connected to a switch rod or tie bar the wide dimension of which is horizontally disposed, then the portion 20 will be arranged so as to straddle such horizontally disposed rod or bar.

The connecting portion 20 is provided with spaced pairs of openings through the arms of the portion with the openings in one arm aligning with the openings in the other arm. The openings in the arms of the portion 20 align with openings through the switch rod or tie bar and bolts 23 extend through said openings in the arms of the portion 20 and the rod and secure the clips to the rods. The bolts 23 are provided with heads 24 located between outstanding ribs 25 formed on the arms of the connecting portion 20. Nuts 26 are screwed upon the bolts 23 and said nuts also are located intermediate the ribs 25. Suitable cotter pins 27 extend through the bolts 23 and hold the nuts 26 in place. The ribs 25 prevent the bolts from turning in the openings while lock washers 26a mounted on the bolts between the nuts 26 and the portion 20 bring the nuts out far enough to clear the ribs 25. This arrangement permits of putting the bolts in from either side, as may be most convenient on account of clearance conditions.

The contacting portion 21 of the clip or lug has one face engaging the outer planar side of the reenforcing bar that is secured to the switch point. The face of the contacting portion 21 which engages the reenforcing bar may be straight or otherwise shaped, but preferably that part of the face that is in contact with the bar is curved on an arc of large radius as indicated at 28, wherefore relative rocking movement can occur between the portion 21 of the clip or lug and the reenforcing bar. The portion 21 is provided adjacent each of its ends and on opposite sides of the intermediate portion 22 with openings 29 that align with openings in the reenforcing bars 15 and 16 and the switch point 12. Headed bolts 30 pass through these aligned openings with the heads 31 of said bolts located in recesses formed on the inner side of the reenforcing bar 15. Flanged spacer sleeves 32 are mounted on the bolts 30 outwardly of the portion 21 of the clip or lug and coil springs 33 surround said sleeves.

and have one end abutting the flange of the sleeve and the opposite end abutting against the outer side of the portion 21 of the clips or lugs. Securing nuts 35 are mounted on the bolts 30 and held in place by cotter pins 36 passing through the bolts. The springs 33 act to hold the contacting portion 21 in tight operative or contacting relationship with the planar outer side of the reenforcing bar 16, thus obviating looseness between the contacting surfaces of the reenforcing bar and of the clip or lug thereby reducing to a minimum wear on such surfaces. The action of the springs 33 can be adjusted by tightening or loosening the nuts 35 as will be clearly understood. The sleeves 32 are provided as a safety measure in case the springs 33 should break. The sleeves 32 are so sized as to allow only about $\frac{1}{8}$ to $\frac{1}{16}$ of an inch looseness in the bolts 30 in the absence of the springs 33. When the switch point is in closed position the bolts 30 actually perform very little function as the clip or lug is pressed directly against the reenforcing bar through the action of the force applied to the tie bar. However, when the switch point is opened these bolts perform the function of pulling the switch point to open position and if the sleeves were not provided and the springs 33 should become broken the switch point would lag behind until the portion 21 engaged the nuts 35. Although coil springs 33 are shown herein as acting to maintain the clips or lugs tightly against the reenforcing bars of the switch points, it will be understood that other forms of spring or resilient means might be employed for this purpose as, for example, rubber blocks might be mounted on the bolts 30 and interposed between the contacting portion 21 and the nuts 35.

It will be understood that when the switch points are thrown from one operative position to the other operative position the clips or lugs can move or rock or roll relatively to the switch points, that is, the clips or lugs can assume different angular positions relative to the points, such movement being permitted by the compression or expansion of the springs 33 or of such equivalent resilient means as may be used in place of the springs.

It will further be understood that inasmuch as the surface 28 of the portion 21 of the clips or lugs is rounded as indicated that said clips or lugs will have a smooth, rolling or rocking movement relative to the switch points and consequently the throwing of the switch points from one operative position to the other operative position will be facilitated and the setting up of stresses in the switch rods will be reduced to a minimum.

In Fig. 9 the rocking movements of the clips or lugs relative to the switch points are diagrammatically indicated and it will be noted that any tendency of the switch rods to bend is substantially eliminated.

Referring to Figs. 6, 7 and 8 wherein a modified form of switch clip or lug embodying the invention is disclosed, it will be seen that the switch rods or tie bars 18 are connected to the clips or lugs by means of a connecting portion 37 which is similar to the connecting portion 20 of the previously described form or embodiment of connecting clip or lug. In describing the connecting clip or lug of the present modified form the different parts of the switch point and the main rails thereof will be given the same reference characters as in the first described form. Integral with the connecting portion 37 the mod-

ified clip or lug is provided with an upwardly and then horizontally extending portion 38, the outer end surface of which portion contacts the reenforcing bar 16. This outer end surface of the portion 38 is preferably curved as indicated at 39, see Fig. 10. The portion 38 is provided with an inwardly facing spring housing recess 40 in which recess is mounted a coil spring 41 extending outwardly of the recess and overlying the portion 37 of the clip or lug. A securing or connecting member is included in this modified clip or lug construction and said member, illustrated per se in inverted position in Fig. 11, is provided with a housing portion 42 which embraces or fits upon the portion 38 and acts as a housing for the extended end of the spring 41 which abuts against the inner side of the rear wall of said housing portion 42. The securing or connecting member also has a flange portion 43 which on opposite sides of the housing portion is provided with openings that align with openings in the reenforcing bar and the switch point and through which the headed bolts 30 can pass. Suitable nuts 35 and cotter pins 36 are mounted on the bolts 30 preferably with spring lock washers interposed between said nuts and the flange portion 43. It will be seen that the spring 41 acts to maintain the surface 39 of the portion 38 in close contact with the reenforcing bar 16 and also serves the purpose of maintaining the flange portion 43 tightly against the nuts 35 or against the lock washers to thus hold the bolts 30 firmly in place. It will be noted that clearance is provided between the opposite sides of the portion 38 and the inner side walls of the housing portion 42, wherefore the portion 38 of the clip or lug may assume different angular positions relative to the switch point and to the connecting or securing member when the switch point is moved to or from closed or open position, it being noted that the flange portion 43 will remain tightly bolted to the switch point at all times.

In both of the forms of construction embodying the invention and which have been described herein for purposes of illustration it will be observed that there are no pin and socket connections wherein the pins may be sheared or bent during the use of the clips or lugs and during the throwing of the switch points. Therefore the life of the clips or lugs is materially increased and the maintenance of the switch is greatly facilitated. It will also have been noted from the foregoing detailed description that devices embodying the invention adequately and fully attain the objects hereinbefore enumerated and provide the desired advantages.

Although several forms of the invention have been illustrated and described herein it will be understood that the invention is susceptible of various modifications and adaptations within the scope of the appended claims.

Having thus described our invention, we claim:

1. Means for connecting a switch rod to a switch point comprising a switch clip or lug having a portion secured to the switch rod and a second portion rigidly connected to said first portion and having a surface part contacting and movably bearing against a surface of the switch point, and means operatively associated with and movable relative to said second portion and operatively connecting said second portion to the switch point to have movement relative thereto whereby said surface part may have relative angular contacting and bearing movement on
- 65 70 75 said surface of the switch point and including

bolts extending through and spaced longitudinally of the switch point, resilient means abutting against said second portion to maintain said surface part thereof in tensioned engagement with said switch point surface, and means through which said bolts extend and having an abutting part engaging said resilient means and movable relative to said second portion, and means carried by said bolts in predetermined position thereon and engaging the said means through which the bolts extend.

2. Means for connecting a switch rod to a switch point as defined in claim 1 and wherein said surface part of said second portion is curved and rocks on said switch point surface in the longitudinal direction of the switch point.

3. Means for connecting a switch rod to a switch point comprising a switch clip or lug having a portion secured to the switch rod and a second portion rigidly connected to said first portion and extending longitudinally of the switch point and contacting and movably bearing against a surface of the switch point, bolts spaced longitudinally of the switch point and extending therethrough and through said second portion, members carried by said bolts in fixed predetermined position thereon and spaced from said second portion, and resilient means interposed between said members and said second portion and acting to maintain said second portion in tensioned engagement with said switch point surface but allowing relative angular movement between said second portion and said switch point surface.

4. Means for connecting a switch rod to a switch point as defined in claim 3 and wherein said second portion has its surface which contacts and bears against a surface of the switch point curved in the longitudinal direction with respect to said switch point wherefore said second portion may have rocking movement relative to said switch point.

5. Means for connecting a switch rod to a switch point as defined in claim 3 and wherein spacer sleeves are movably mounted on said bolts intermediate said members and said second portion while said resilient means are coil springs surrounding said sleeves and abutting said sec-

ond portion and a flange formed on said sleeves.

6. Means for connecting a switch rod to a switch point comprising a switch clip or lug having a portion connected to the switch rod and a second portion rigidly connected with the first portion and having a surface contacting and movably bearing against a surface of the switch point, said second portion being provided with a recess, resilient means mounted in said recess, and a securing member having a housing portion embracing said second portion and movable relatively thereto and forming an abutment for said resilient means, said securing member having flanges extending longitudinally of the switch point and in contact therewith, bolts extending through said switch point and said flanges, and means carried by said bolts engaging said flanges to prevent movement of said flanges relative to said switch point.

7. Means for connecting a switch rod to a switch point as defined in claim 6 and wherein the surface of said second portion which movably bears against a surface of the switch point is a curved surface and the relative movement between the switch point and said second portion is a rocking movement.
